UNITED STATES PATENT OFFICE

138,744

DESIGN FOR A CIGARETTE BOX OR THE LIKE

Benjamin E. Lawrence, Chicago, Ill.

Application May 29, 1944, Serial No. 113,790

Term of patent 3½ years

(Cl. D85—2)

To all whom it may concern:

Be it known that I, Benjamin E. Lawrence, a citizen of the United States, residing at Chicago, in the county of Cook and State of Illinois, have invented a new, original, and ornamental Design for a Cigarette Box or the like, of which the following is a specification, reference being had to the accompanying drawings, forming a part thereof.

In the drawings—

Fig. 1 is an enlarged plan view of a cigarette box, showing my new design,

Fig. 2 is a side elevational view thereof,

Fig. 3 is a rear end view, and

Fig. 4 is a perspective view with the cover removed.

I claim:

The ornamental design for a cigarette box or the like, as shown.

BENJAMIN E. LAWRENCE.
